PAGE 3

FIG. 1 is a side perspective view of a hay crushing implement embodying our new design, looking from the left side of the machine;

FIG. 2 is a rear perspective view thereof;

FIG. 3 is a front perspective view thereof; and

FIG. 4 is a top plan view thereof.

The dominant features of our design reside in the full line portions of the drawings.

We claim:

The ornamental design for a hay crushing implement, as shown and described.
